UNITED STATES PATENT OFFICE

ANDREWS ALLEN, OF GLENCOE, ILLINOIS, ASSIGNOR TO ALLEN & GARCIA COMPANY,
OF CHICAGO, ILLINOIS, A CORPORATION OF ILLINOIS

ROTARY CAR DUMPER

Application filed July 5, 1928. Serial No. 290,412.

This invention relates to an improved rotary car dumper, and more particularly to an apparatus in which an open top car with solid sides and ends is rotated upon a horizontal axis parallel with the supporting track in such a manner as to discharge its lading or contents into a hopper or other container disposed beneath the dumper.

The invention relates particularly to a dumping apparatus of the type in which a continuous train of loaded cars is moved by successive stages through a rotary cylindrical dumper containing a section of the track. As each car comes within the dumper, the train is halted, the car secured within the rotary cage, and the cage is given one complete rotation, whereby the contents of the car is spilled into a hopper and the car returned to its normal upright position. The car is then unlocked and the train moves on until another car is located within the cylindrical dumper, when the dumping process is repeated.

The general object of this invention is to provide an improved apparatus of this type which will operate smoothly and regularly by means of automatic control, so that normally only one manual operation is required to start the rotation of the dumper which will then perform its cycle without further attention from the operator. The dumper can, however, be stopped at any point in the cycle of operation and then returned to normal position.

Another object is to provide a rotatable cage of improved construction, involving strength and simplicity and so designed that all wearing parts can be easily repaired or renewed without entirely dis-assembling the frame, and so designed that the friction of the dumper, when turning, shall be as small as possible.

Another object is to provide improved means for supporting the cage for rotation about its axis, whereby frictional loss is minimized.

Another object is to provide improved means for rotating the cage, in combination with an automatic controller for same, which is not connected directly with the cage, but

is geared thereto so as to rotate synchronously therewith.

Another object is to provide an improved yieldable cage stop whereby the cage when manually released can make one complete 55 rotation and then will be yieldingly halted in normal upright position.

Another object is to provide a single means for releasing the cage from the stops and simultaneously starting the cage-rotating 60 means.

Another object is to provide improved shields for deflecting material which might otherwise spill out of the ends of the cage, back into the receiving hopper. 65

Another object is to provide improved stationary shields, carried by the non-rotary track sections at the respective ends of the cage, which cooperate with the end deflectors 70 of the cage to direct material back into the hopper.

Another object is to provide a cage adapted to receive either of two types of standard cars, and alternatively lock either type of car within the cage automatically. 75

Another object is to provide improved means for automatically locking each car in position within the cage, and for automatically releasing the car locks after the dumping operation has been completed. 80

Another object is to provide a movable spill shield on the cage which is moved into and out of operative position automatically, along with the car locking means.

Other objects and advantages of this invention will be more apparent from the following detailed description of one approved form of the apparatus.

In the accompanying drawings:

Fig. 1 is a longitudinal vertical section 90 through the apparatus.

Fig. 2 is a plan view, on a somewhat smaller scale, partially broken away.

Fig. 3 is a vertical section, taken substantially on the line 3—3 of Fig. 1, showing the position of the parts before the car has been moved into the cage. 95

Fig. 4 is a view similar to Fig. 3, but showing the car locking means in engagement with the car. 100

Fig. 5 is an end view of the apparatus, looking substantially from the line 5—5 of Fig. 1. The cage 1 is in the form of a cylindrical drum positioned horizontally to rotate about its longitudinal axis above a hopper, the mouth of which is indicated at 2. The cage 1 is built up of metal plates and angle sections so as to form a substantially closed drum, except for a central longitudinal passage 3 therethrough which receives the car to be dumped, and an upper spill opening 4, through which the contents of the car is dumped when the cage is inverted. Some-
what less than the lower half of the drum 10 is divided into three separated compartments 9, 10, and 11, by the transverse end partitions 5 and 6, and the intermediate partitions 7 and 15 8. Supported by the transverse angles 12 at the tops of the several partitions 5, 6, 7 and 8, 20 are longitudinally extending angle beams 13 which carry the rails 14, which extend from end to end of the cage parallel with its axis of rotation, that is from the end partition 5 to the end partition 6. Extending up from 25 the transverse partitions at either side of the car-receiving passage 3, are parallel vertical walls 15 and 16, substantially the height of a car, from the upper ends of which the stationary spill shields or walls 17 and 18 ex-
20 tend radially to the outer circumference of the drum or cage. Practically the entire outer surface of the drum from the spill wall 18 clockwise around to the spill wall 17 is enclosed by arcuate plates. The smaller upper 30 part of the drum from wall 17 to wall 18 at the top is opened to provide the spill opening 4, and at the ends of the cage, beyond the ends of the opening 4, the circumferential surface of the drum is completed, as indicated at 35 19 and 20, by means of arcuate plates and suitable strengthening members. Complete annular shields 21 and 22 (hereinafter described more in detail) extend outwardly beyond the respective ends of the cage proper, substantially as continuations of the outer cylindrical casing of the cage. Openings 23 (see Fig. 2) are formed in the outer casing of the drum, leading to the compartments 9, 10 and 11, so that coal or other material which 40 50 may spill between the tracks or otherwise fall into the interior of the drum may drain out when the cage is inverted.

Circular supporting tracks 24 are secured circumferentially about the periphery of the cage adjacent its ends, preferably in line with the end partitions 5 and 6. Annular driving racks 25 are also secured to the cage adjacent its ends, as here shown the racks 25 being mounted on flanges 26 at the outer sides 55 of the supporting rails 24. The rails 24 rest on supporting rollers 27 carried by suitable brackets 28. In former dumpers of this type, it has been thought necessary to set the supporting trunnions for these rollers on radial lines at approximately 45° with the vertical

on each side of the axis of the drum or cage. I have discovered that substantially half of this angle is sufficient to provide stability and the result is that instead of a trunnion load of 1.414 times the weight of the car and lading, I have a trunnion load of only 1.08, which decreases proportionately the power required to revolve the dumper. In order to prevent a possible tilting of the dumper 70 on its supports, which might throw the driving gears (hereinafter described) out of mesh, a pair of idler rollers 29 are provided which engage the supporting rails 24 adjacent the horizontal plane passing through the axis of the drum and substantially diametri- 75 cally opposite the point where the driving pinions engage the racks 25.

A pair of coaxial drive shafts 30 and 31, mounted parallel with the axis of the drum at one side thereof, are driven through suitable 80 gearing 32 from the motor 33. The shafts 30 and 31 carry gears or pinions 34 and 35 at their outer ends, meshing with the respective racks 25 on the cage. A pinion 36 secured on shaft 31 drives a gear 37 on the shaft 38 of an 85 automatic controller 39 which governs the driving motor 33. The gear ratio is such that shaft 38 of the controller will make one complete revolution for each revolution of the cage 1, so that the controller will always rotate 90 in complete synchronism with the cage. The controller 39 is of the type embodying a plurality of rotating cams and cooperating contact members whereby, after the first electrical contact has been made, the contacts in the controller will automatically accelerate the cage rapidly to its maximum speed, then decelerate it to a very low speed and finally cut off the power just before the cage completes 95 its revolution and drifts into the latch mechanism, hereinafter described. Automatic electric controllers of this type are well known, and it has not been deemed necessary to describe or show same in detail. However, devices of this kind have formerly been devised 100 which depend on contacts made by points on the cage itself. These devices are defective, in that the apparatus is subject to injury by contact with outside objects and dangerous, since it cannot be entirely protected. According 105 to the present invention, the driving mechanism is geared positively to the cage through spur gearing and the controller is also geared to a secondary counter shaft in such manner 110 that it will always rotate in complete synchronism with the cage. In this manner the controller may be so positioned that it will be fully protected, and readily accessible for 115 adjustment.

Mounted adjacent each end of the cage is a vertical standard 40 (see Figs. 1, 2 and 5), in which is slidable a carriage 41, positioned between two heavy compression springs 42 and 43 so that the carriage is yieldable vertically 120 in either direction, but will normally be held 125

in the central position shown in the drawings. Pivoted in carriage 41 are a pair of latches 44 and 45, the ends of which normally project outwardly toward the cage so as to engage opposite sides of a lug 46 fixed to the cage. When the lug is engaged between the latches 44 and 45, the cage is locked in its normal upright position. The upper latch 44 is pivoted intermediately at 47 to carriage 41, and has a short upper arm 48 adapted to engage a fixed stop 49 so as to limit the outward movement of the lower arm of the latch which engages the lug 46. A third arm 50 on the latch member is pivotally connected with a rod 51 which extends up through a spring 52 which acts to normally hold the latch 44 yieldably in the position shown in the drawings. However, when the cage 1 is rotated clockwise, (Fig. 5) the lug 46 on the cage will depress the latch 44 against the action of spring 52 until the lug 46 reaches the position shown in the drawings, at which time the latch 44 will spring back in engagement with the upper face of the lug. The lower latch member 45 is pivoted intermediately at 53 and has a lower arm 54 adapted to engage a fixed stop 55 to hold the latch in the locking position shown. Arm 54 has a pin and slot connection 56 with a crank arm 57 extending upwardly from a rock shaft 58 which extends longitudinally parallel with the axis of the cage. It is to be understood that all of the latch mechanism so far described is duplicated at each end of the cage. A manually operable lever 59 is secured to one end of rock shaft 58, so that by moving this lever in a counter-clockwise direction (Fig. 5) the lower latch members 45 will be swung inwardly out of engagement with the lugs 46 so that the cage is released for rotation in a clockwise direction. A cam lug 60 on the lever 59 is adapted to engage a starting switch 61 of any approved type, when the lever is swung in the direction to release the latches 45, this switch 61 serving to complete the first electrical contact for controller 39 to initiate the cycle of rotating movements of the cage 1. After the rotation of the cage has commenced, the manually operable lever 59 is moved back to the normal position shown in the drawings, and after the cage has completed one revolution the lugs 46 will snap into place between the latches 44 and 45 so as to lock the cage in normal upright position. Of course, the controller 39 will stop the motor 33 at this time so that power is no longer being applied to the cage to rotate same. Since the entire latch assembly is floating between the compression springs 42 and 43, it can yield to some extent in either direction to cushion the shock of stopping the cage.

It will be understood that the electric controlling connections for motor 33 include a cut-out switch and reversing mechanism (not here shown) so that the rotation of carriage 1 can, if necessary, be stopped at any point in

its rotation, and reversed to bring the cage back to its normal upright position. In such case, the lower latches 45 will yield inwardly to permit the lugs 46 to return to locking position, in an obvious manner.

The stationary tracks 62 and 63 leading to and from the cage project into the annular end shields 21 and 22 so as to meet the respective ends of tracks 14 in the cage. These inwardly projecting ends of tracks 62 and 63 are carried by cantilever I-beams 64 secured to fixed anchorages 65. It will be understood that a continuous train of cars joined by swivel connections are moved through this apparatus, so that when one car is carried by the cage 1 and rotated to dump its contents, the immediately adjacent cars will remain stationary on the fixed trackways 62 and 63.

In order to prevent the coal or other material from spilling out of the ends of the cage 1 during the dumping operation, the annular end shields 21 and 22, hereinabove referred to, are provided, these shields projecting outwardly around the ends of the fixed tracks 62 and 63. These shields can be extended without difficulty far enough to envelop the ends of the next cars at each end of the dumper, and will catch perfectly all lading that may fall over the end of the car or may be crowded off during rotation of the dumper. Each of the cylindrical shields 21 and 22 is finished at the outer end by an inwardly extending annular ring or flange 66, the outside diameter of which is the diameter of the cage, and the inner diameter of which may be the least diameter that will clear the car and its lading. A substantially semi-circular shield 67 is hung from the beams 64 which support the fixed rails 62 and 63 at each end of the cage, this stationary shield 67 projecting downwardly inside of the annular end ring or flange 66 so that no lading falling through between the fixed rails adjacent the ends of the cage can escape being caught by the cylindrical shields 21 and 22. Within the upper portion of each shield 21 and 22 is a radially extending deflector 68 extending diagonally from the outer ring 66 inwardly toward the spill opening 4, so that as the cage revolves the material caught within the cylindrical shields 21 and 22 will be directed inwardly by the deflectors 68 and dumped through opening 4 into the hopper 2. It will be noted that the portions 19 and 20 of the cage, and the deflectors 68, extend a sufficient distance inside of the supporting rails 24 and rollers 27 so that these wheels or rollers and their bearings will be protected from falling lading. The mouth of hopper 2 need not be materially wider than the spill opening 4, and since this hopper is located between the supporting rollers 27 the sides of the hopper serve as an additional means for protecting the rollers from injury by the falling lading. Counter-weights 69 are po-

sitioned within the space behind deflectors 68 and between these deflectors and the end flanges 66. These counter-weights tend to balance the preponderance of weight at the diametrically opposite side of the cage.

It is necessary that means be provided to hold the car firmly in position within the cage during the dumping operation. The present apparatus is adapted to receive and hold either of two standard types of dump-car now in use. One of these cars, as shown in Fig. 5, has a width sufficient to substantially fill the passage 3 between the side walls 15 and 16. Car-holding angles 70 are secured to the side walls 15 and 16, and angle brackets 71 secured to the respective sides of the car engage under the fixed angles 70 as the car moves into the cage. These inter-engaging angles will support the car in an obvious manner during the rotation of the cage. It will be apparent that the spill shields 17 and 18 built in the cage extend radially substantially from the opposite side edges of the upper open side of the car so that substantially all of the material held within the car will be directed outwardly through opening 4 as the dumper is rotated.

Another standard type of car is illustrated in Fig. 4, this car being much narrower than the passage 3. For cooperation with this type of car, pivoted car stops or horns are provided to swing up and engage over the wheels 72 of the car, thus holding the car down against the supporting rails 14. Means is provided to automatically engage these horns with the wheels as the car moves into position within the cage, and to release the horns after the dumping operation has been completed. There are two independently operable sets of horns 73 and 74, the horns 73 being adapted to engage the front wheels of the car as it moves into position within the cage, and the horns 74 subsequently engaging the rear wheels after the car has been stopped against the front horns 73. Substantially identical means is provided for automatically moving each set of horns 73 and 74 to locking position. The mechanism is shown in side elevation in Fig. 1, and Fig. 4 shows the horns in locking position. In Fig. 3 both sets of horns are shown locked in released position, but the horns 73 are shown in dotted lines after they have been moved to locking position. Each set of horns, (for example the horns 74), are mounted at their lower ends on shafts 75, which are mounted for rocking movement in the cage structure. Crank arms 76 secured to shafts 75 are connected through links 77 with the oppositely projecting lever arms 78 and 79 of a rocker member centrally pivoted at 80 on a fixed bracket 81. An upper arm 82 of the rocker member is pivoted at 83 to a rod or link 84 which projects through a compression spring 85, so mounted as to normally move the

rocker member to the position shown in Fig. 4, whereby through the link mechanism above described, the horns 74 will be swung upwardly into locking position about the rear wheels 72. It will be understood that an exactly similar set of levers and operating mechanisms is provided for the horns 73, so that each set of horns may be independently moved to locking position by the expansion of its spring 85.

Each rocker member comprises a downwardly extending crank arm 86, from one side of the lower end of which projects a pin or stud 87. A rock shaft 88 extends longitudinally near one side of cage 1. A crank arm 89 extending downwardly from shaft 88 pivotally supports one end of a latch bar 90, the opposite end of bar 90 being pivoted at 91 to the lower end of a rod 92 which extends slidably upward through a bearing 93, a spring 94, surrounding the rod 92 and normally tending to force the latch bar 90 downwardly. The central portion of bar 90 is enlarged, as indicated at 95, and a rather long vertical slot 96 in this portion of the bar receives the pin 87 on the arm 86 of the rocker member which actuates the horns 74. A cam lug 97 formed on the bottom of bar 90 is adapted to engage behind a fixed stop 98 in the cage frame, as shown in Fig. 3, and thus holds the rocker in this position against the force of spring 85, with the horns 74 in released position, as shown in Fig. 3. A vertical rod 99 has a lug 100 at its lower end extending under the arm 90. The upper end of rod 99 is pivoted at 101 to one arm 102 of a bell-crank pivoted at 103 in the cage frame, the other arm 104 of the bell-crank projecting upwardly into the path of a lug or cam 105 carried by the car.

A second latch bar 106 (see dotted lines Fig. 3) is formed with a slot 107 adapted to receive the stud 87 on the rocker member which operates the other pair of horns 73. Latch bar 106 is mounted parallel with the bar 90 but spaced laterally therefrom, as indicated in Fig. 1, and is connected at one end with the rock shaft 88 by a crank arm similar to the arm 89, and is yieldably forced down at its other end by a spring 115 pressed rod similar to the rod 92. The latch bar 106 has no cam lug similar to the lug 97 on bar 90, and the slot 107 in bar 106 is much shorter than the slot 96 in the bar 90, so that when the latch bar 106 is raised, the slot 107 may be completely released from the stud 87 on the rocker member. As shown in Fig. 3 in dotted lines, the latch bar 106 has been raised to disengage the lug 87, and the rocker mechanism which actuates the horns 73 has been swung counterclockwise by its spring 85 to bring the horns 73 into locking engagement with the car wheels, as indicated in dotted lines. A vertical rod or bar 109 has a lug 110 at its lower

end adapted to engage beneath the latch bar 106 to raise same and release the bar from stud 87. The upper end of rod 109 is pivoted to one arm 111 of a bell-crank pivoted at 112, the other arm 113 of the bell-crank being connected by link 114 with the lower arm of a bell-crank 115 pivoted at 116 in the cage frame. The upper arm 117 of the bell-crank projects up into the path of the lug 105 on the car.

A crank arm 118 extending upwardly from rock shaft 88 is connected by link 119 with the shaft 120 of a releasing roller 121. Shaft 120 is also supported by links 122 pivoted at 15 their upper ends 123 in the cage frame. When the horns are in released position, as indicated in solid lines in Fig. 3, the roller 121 will be in the position shown in that figure. When the horns are moved to locking 20 engagement with the wheels 72 of the car, the roller 121 will be projected outwardly through a suitable opening in the casing of the cage, to the position shown in Fig. 4. As the cage 1 approaches the end of its rotation, roller 121 will engage the fixed cam 124 25 mounted adjacent the cage, and will be again pushed into the position shown in Fig. 3 to return the horns to their unlocked positions.

In describing the operation of this car locking mechanism, we will first assume that the parts are all in the released positions indicated in solid lines in Fig. 3. As a car moves into the cage, the cam or lug 105, positioned beneath the car, will first engage the lever arm 117, which through the link and lever connections previously described, will elevate the latch bar 106 to release the pin 35 87 on the rocker which actuates the horns 73. The corresponding spring 85 will now expand to swing the horns 73 upwardly to the dotted line position indicated in Fig. 3. As the forward wheels 72 of the car move forward into engagement with horns 73, the cam 40 105 will engage the second lever arm 104, thus lifting the other latch bar 90 so as to release the locking lug 97 from the fixed stop 98. During this movement, the stud 87 on the rocker member which actuates the horns 74 will not become disengaged from slot 96 in 45 latch bar 90, this slot 96 being of sufficient length to permit the vertical movement of bar 90 sufficient to release lug 97 from stop 98. The other spring 85 will now swing counter-clockwise the operating mechanism 50 for horns 74, thus swinging these horns up into engagement with the rear wheels 72 on the car. Since stud 87 remains in engagement with slot 96 in latch bar 90, this bar will be drawn toward the right in unison 55 with the rocker member, thus swinging the rock shaft 88 and projecting roller 121 to the position shown in Fig. 4. At the same time, latch bar 106 will be moved to the right in unison with latch bar 90, until the slot 107 60 in this bar is again moved into engagement

with stud 87 on the corresponding rocker member, by the expansion of spring 94. The car is now locked firmly in position by engagement of the horns 73 and 74 with the respective wheels of the car.

As the revolution of the cage is completed, roller 21 will engage the fixed cam 124 and be pushed back into the cage so as to swing rock shaft 88 in a clockwise direction. This will draw both latch bars 90 and 106 toward 75 the left, so as to release both sets of horns 73 and 74 against the resistance of the springs 85. At the completion of this movement the locking lug 97 on bar 90 will snap into engagement with the fixed stop 98, thus locking 80 all of the parts in their original released position.

It will be noted that with the narrower type of car shown in Fig. 4, the fixed spill shield 18 in the cage does not extend into as close engagement with the adjacent side of the car as it does with the wider car shown in Fig. 5. Accordingly, an auxiliary shield or spill plate 125 is pivoted at 126 along the lower edge of shield 18 so that it may be swung out against the side of the car and form an extension of shield 18 to prevent the coal or other lading from spilling down inside of the cage. The free edge or shield 125 is connected by a link 126a with the upper arm 127 of a lever, intermediately pivoted at 128 in the cage. The lower arm 129 of this lever is connected, through link 130, with a crank arm 131, secured to rock shaft 88. It will be apparent that when this rock shaft 88 is 95 swung counter-clockwise, as the horns 74 are moved to locking position, the lever connection just described will swing shield 125 up to the operative position shown in Fig. 4. When the horns are automatically released, shield 125 will automatically be withdrawn to the inoperative position shown in Figs. 3 and 5. When the larger type of car, indicated in Fig. 5, enters the cage, the car locking mechanism hereinabove described will not be 100 operated since no lug 105 for operating the levers 104 and 117 is provided beneath this car. Consequently, the auxiliary shield 125 will remain in inoperative position, as indicated in Fig. 5.

In the general operation of this dumping mechanism, a train of loaded cars, joined by suitable swivel couplings, are drawn through the cage so as to successively bring each car into position within the cage. If the car is 105 of the larger type, shown in Fig. 5, the angle members 71 on the car will move beneath the angles 70 in the cage and automatically lock the car in position. If the car is of the smaller type shown in Fig. 4, the locking horns 73 and 74 will be automatically moved into engagement with the car wheels and the auxiliary spill shield 125 will be moved up into operative position, all as previously described. It will be understood that the angles 70 and 110

the vertical walls 15 and 16 are cut away as necessary to permit the horns 73 and 74 to swing to and from their operative positions. The operator now swings over the lever 59 to release the cage and close switch 61, thereby placing automatic controller 39 in control of driving motor 33. This automatically controlled driving mechanism will now cause one complete rotation of the cage 1 and the car carried thereby, so as to dump the lading from the car. Material that is caught at this time, or has been previously caught within the end shields 21 and 22, will be simultaneously deflected into the hopper by the angular deflectors 68. Any material that has fallen into the compartments 9, 10 and 11 of the drum will be discharged through openings 23. After the car has completed its rotation, the lugs 46 on the cage will drift into engagement with the yieldable latches 44 and 45 and once more lock the cage in its normal upright position. At substantially the same time, the horns 73 and 74 will be released from the car and the spill shield 125 will be swung down into inoperative position. The train is now moved forward so as to bring the succeeding car into the cage and the dumping operation is then repeated.

It should be noted that this dumper is designed for operation with the longer cars, that is the cars of usual length, and that the described operation with continuous coupled trips or trains of cars will ordinarily be possible only with these longer cars. In some instances shorter cars are used and these cars must be uncoupled from the train and dumped separately else the adjacent cars will project into the dumper during the dumping operation. The horns engaging over the car wheels provide a means for holding these detached shorter cars in position longitudinally as well as holding the cars from falling out of the cage during its rotation.

While a preferred form of cylindrical cage has been disclosed, it will be apparent that only the tracks 24 and driving racks 25 need be circular or cylindrical, and the remainder of the cage may have any other desired or convenient structural form. The cylindrical form here disclosed gives strength and rigidity with a minimum of material.

While it is convenient to form the end shields 21 and 22 as annular continuations of the cylindrical cage, this conformation is not at all necessary. The shields may have a different cross-sectional configuration. Cylindrical end shields are usually best adapted to perform the specified functions, and they tend to stiffen the cage and lend strength and rigidity thereto, particularly if the cage is largely open, or of other than cylindrical conformation.

Numerous other structural changes or equivalent constructions will be possible throughout the combination without depart-

ing from the scope of the invention as defined by the following claims.

I claim:

1. In a car dumping apparatus, a rotary cage, means for supporting a car therein, the cage having a spill opening above the car whereby the contents of the car may be dumped from the cage when the cage is inverted, means positioned adjacent the ends of the cage for supporting the cage for rotation, and annular shields projecting outwardly from the ends of the cage for catching material that would otherwise spill from the ends of the cage.

2. In a car dumping apparatus, a rotary cage, means for supporting a car therein, the cage having a spill opening above the car whereby the contents of the car may be dumped from the cage when the cage is inverted, means positioned adjacent the ends of the cage for supporting the cage for rotation, and annular shields projecting outwardly from the ends of the cage for catching material that would otherwise spill from the ends of the cage, there being an annular flange projecting radially inward from the end of each shield.

3. In a car dumping apparatus, a rotary cage, means for supporting a car therein, the cage having a spill opening above the car whereby the contents of the car may be dumped from the cage when the cage is inverted, means positioned adjacent the ends of the cage for supporting the cage for rotation, and annular shields projecting outwardly from the ends of the cage for catching material that would otherwise spill from the ends of the cage and deflecting means mounted within the shields for directing material caught therein to the spill opening of the cage.

4. In a car dumping apparatus, a rotary cage, means for supporting a car therein, the cage having a spill opening above the car whereby the contents of the car may be dumped from the cage when the cage is inverted, means positioned adjacent the ends of the cage for supporting the cage for rotation, and annular shields projecting outwardly from the ends of the cage for catching material that would otherwise spill from the ends of the cage, there being an annular flange projecting radially inward from the end of each shield and diagonally positioned deflectors in the shields extending from the annular flange to openings leading to the spill opening of the cage.

5. In a car dumping apparatus, a rotary cage, a trackway mounted in the cage from end to end thereof, means for holding a car on the trackway, stationary trackways mounted in alignment with the trackway in the cage, the cage having a spill opening above the car whereby the contents of the car may be dumped from the cage when the cage is inverted, means positioned adjacent the

ends of the cage for supporting the cage for rotation, and annular shields projecting outwardly from the cage and surrounding the ends of the stationary tracks, and means within the shields for deflecting material caught thereby into the spill opening of the cage.

6. In a car dumping apparatus, a rotary cage, a trackway mounted in the cage from end to end thereof, means for holding a car on the trackway, stationary trackways mounted in alignment with the trackway in the cage, the cage having a spill opening above the car whereby the contents of the car may be dumped from the cage when the cage is inverted, means positioned adjacent the ends of the cage for supporting the cage for rotation, and annular shields projecting outwardly from the cage and surrounding the ends of the stationary tracks, there being an annular flange projecting radially inward from the end of each shield, and nonrotary substantially semi-cylindrical shields supported by the stationary trackways and extending within the annular flanges of the shields on the cage.
